Charles Henry Givens
INVENTOR

BY Victor J. Evans

ATTORNEY

Leah Givens
I. B. McCallister.
WITNESS:

UNITED STATES PATENT OFFICE.

CHARLES HENRY GIVENS, OF MODESTO, CALIFORNIA.

JACK.

Application filed July 6, 1923. Serial No. 649,913.

To all whom it may concern:

Be it known that I, CHARLES H. GIVENS, a citizen of the United States, residing at Modesto, in the county of Stanislaus and 5 State of California, have invented new and useful Improvements in Jacks, of which the following is a specification.

This invention relates to a novel form of jack, the general object of the invention 10 being to provide means whereby the jack can be raised and lowered by a hand lever without manipulating a dog or clutch which is liable to cause injury to the operator.

Another object of the invention is to provide 15 means whereby the jack can be caused to drop without being lowered by a step by step movement and also to provide means for lowering it by a step by step movement.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the sev- 30 eral views, and in which:—

Figure 1 is a front view of the device.

Figure 2 is a side view thereof.

Figure 3 is a rear view.

Figure 4 is a longitudinal sectional view.

Figure 5 is a section on line 5—5 of Figure 4.

Figure 6 is a section on line 6—6 of Figure 4.

In these views 1 indicates a frame which 40 is provided with the platforms 2 and 3. At one of the rear sides the frame is provided with a rack 4. A bar 5 is slidably mounted in holes formed in the two platforms, the bottom of the bar having a foot 6 connected 45 therewith and the top of the bar having a rest 7 swiveled thereto. A vertical slot 8 is formed in the bar and a rack 9 is placed in said slot. A slide 10 is slidably mounted on the bar and is located between the two 50 platforms. A yoke 11 is pivoted to the slide and a catch 12 is pivoted to the yoke in such a manner that it will engage the rack 9 to hold the rack in adjusted position. A hand lever 13 has its forked end pivoted to the 55 lower part of the slide and a flange 14 is formed on the front part of the lower plat-

form for forming a fulcrum for the hand lever.

When using the device the hand lever is pushed downwardly so that it will rock 60 on its fulcrum and thus raise the slide which will also cause the bar to raise as the slide is connected with the bar by the catch. The hand lever is then moved to the right so as to place the foot 6 in engagement with one 65 of the teeth of the rack 4. The hand lever is then raised slightly to permit the slide to drop back upon the lower platform. The hand lever is then raised again to raise the parts another step and at the end of its 70 movement the hand lever is swung to the right again to place the foot in engagement with another notch. This action is kept up until the bar has been raised to a sufficient 75 amount. If the load is to be dropped without a step by step movement the hand lever is lowered a little and at the same time is swung to the left so as to release the foot 80 from the rack 4. Then the hand lever is raised until it strikes the trigger or catch 12 85 to release the same by swinging the yoke 11 and said catch upwardly and this will permit the bar and the load carried thereby to drop. If a gradual downward movement is desired the hand lever is raised slightly 90 and at the same moved a slight distance to the left. The hand lever is then moved a sufficient distance to place the foot 6 over a notch of the rack 4 and then the hand lever is lifted until it strikes the catch hard 95 enough to release the same so that the foot on the bar can drop into the notch of rack 4. This action is repeated until the parts are in lowered position.

From the foregoing it will be seen that 95 it is not necessary to move a dog or catch which is liable to injure the fingers as all the movements are made with the hand lever.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A jack of the class described comprising a frame having a rack bar at its lower part, a bar slidably mounted in the frame, a foot on the bar engaging the rack bar, a

slide on the bar, a catch on the slide, a rack bar on the bar with which the catch engages and a hand lever pivoted to the slide and having a part for engaging the catch.

5. 2. A jack of the class described comprising a frame, including an upper and lower platform having openings therein, a rack bar on the lower part of the frame, a rod passing through the openings in the platforms, a foot on the lower end of the rod for engaging the rack bar, a slide on the rod and arranged between the two platforms, a rack on the bar, a catch on the slide for engaging the rack bar, and a hand lever pivoted to the slide and having a part adapted to engage the catch.

3. A jack of the class described comprising a frame, including an upper and lower platform having openings therein, a rack bar on the lower part of the frame, a rod 20 passing through the openings in the platform, a foot on the lower end of the rod for engaging the rack bar, a slide on the rod and arranged between the two platforms, a rack on the bar, a catch on the 25 slide for engaging the rack bar, a hand lever pivoted to the slide and having a part adapted to engage the catch and a fulcrum for the hand lever on the lower platform.

In testimony whereof I affix my signature.

CHARLES HENRY GIVENS.
